[57] CLAIM

The ornamental design for an electrocardiogram lead
terminal, substantially as shown and described.

DESCRIPTION

FIG. 1 is a perspective view of an electrocardiogram
terminal showing my new design;

FIG. 2 is a top plan view, of the electrocardiogram
terminal;

FIG. 3 is a bottom plan view of the electrocardiogram
terminal shown in FIG. 1;

FIG. 4 is a right hand end view of the electrocardiogram
terminal shown in FIG. 1;

FIG. 5 is a front view of the electrocardiogram terminal
shown in FIG. 1; and

FIG. 6 is a left hand end view of the electrocardiogram
terminal shown in FIG. 2.

FIG. 1

FIG. 2

FIG. 3

FIG. 4

FIG. 5

FIG. 6
